CHAIR CONSTRUCTION

Harold Robinson, Detroit, Mich.

Application March 3, 1943, Serial No. 477,889

10 Claims. (Cl. 155—179)

This invention relates to a chair or furniture construction wherein the use of metallic springs is eliminated. More particularly the invention relates to a novel substitute resilient furniture construction where, in place of the now critical coiled springs, is employed a resilient means with substantially equivalent functions.

It is the object of this invention to provide a resilient chair construction consisting of a resilient webbing secured to the furniture frame, together with a secondary webbing or resilient support yieldingly disposed in spaced relation to the first webbing, and adapted to engage the same upon receipt of a compressive force.

This invention therefore relates to the various arrangements of elements and their combinations as more fully set out in the accompanying drawing of which—

Fig. 1 is a partially sectioned side elevational view of a chair construction.

Fig. 2 is a top plan view of the upper resilient support therefor.

Fig. 3 is a bottom plan view of the lower support therefor.

It will be understood that the above drawing illustrates merely a preferable embodiment of the invention, and that other embodiments are contemplated within the scope of the invention as hereafter more fully set out and claimed.

Referring to the drawing, the chair shown in Fig. 1 consists of a substantially rectangular frame 11 with the end members 12 and 13 and the side portions 14 and 15. Suitable legs 16 depend downwardly from the frame, with the back support and arm indicated at 17 and 18 respectively.

Referring to Fig. 1 the chair is fragmentarily shown with the covering upholstery removed. The chair support or seat is given its resiliency by means of the webbing members 19 and 27 which are disposed in parallel spaced relation within the chair frame 11.

The lower webbing shown by the bottom plan view of Fig. 3 consists of interwoven strips 20 and 21 of suitable material, for instance hemp or other fibrous substance characterized by a suitable amount of strength and resiliency. Webbing strips 20 are tacked at their ends at 22 to the side frame members 14 and 15; while on the other hand the interwoven strips 21 extend longitudinally within frame 11. Said strips 21 are stretched over the rigid cross bars 23 and through the slotted portions 24 thereof, and extend downwardly along the outside edges of said cross bars.

Webbing members 21 further extend downward continuously and around the stationary cylindri-

cal shafts 25 for attachment by tacks at 26 to the under surface of the frame members 12 and 13.

It is understood that shafts 25 may be yieldingly secured to the frame 11 permitting a degree of resiliency to the ends of the webbing strips 21, and consequently to the entire lower webbing 19 if desired.

The upper seat support or webbing shown in Fig. 2 consists of a plurality of longitudinal strips 27 disposed within the seat frame 11 and in parallel spaced relation to the lower webbing 19 thereby providing a resilient seat for the chair.

Cylindrical shafts 28 and 29 are loosely disposed within frame 11 with their ends in sliding spaced relation to the side members 14 and 15. Webbing strips 27 are looped at 30 at their opposite ends and the shafts 28 and 29 are disposed therethrough providing a yielding support for the strips of webbing 27 in view of the yielding support of said shafts now described.

Looped members 31, preferably of the same material as members 27 and tacked at 32 to opposite ends of the frame member 12, have disposed therethrough the end portions of the shaft stick 28. Similarly the looped members 33 tacked at 34 to opposite ends of the frame members 13 have disposed therethrough the ends of the shaft 29.

Consequently it is seen that a substantially floating support is given to the shafts 28 and 29 which thereby provide a high degree of resiliency to the top chair webbing strips 27. By virtue of looped members 31 and 33 through which shafts 28 and 29 are disposed respectively, and in view of the interconnecting webbing portions 27, with said shafts also disposed through the loops on the ends thereof, it is seen that said shafts 28 and 29 are susceptible to longitudinal as well as vertical movements.

The chair seat is completed by the substantially resilient padding material 35 provided upon the upper webbing strips 27, over which is usually provided a proper upholstery material not shown herein.

Furthermore additional padding material 36 of a resilient character is disposed between the initially spaced apart upper chair webbing 27 and the lower webbing 19 to complete the chair construction.

Referring to Fig. 2 a looped member 37 is centrally positioned and tacked at 38 to the frame member 12 with the shaft 28 disposed therethrough. It will be noted however that the looped portion 39 of stop member 37 extends

55 continuously around the stationary cylindri-

beyond the loops in the webbing 27 acting merely as a stop or limiting means against extreme longitudinal or vertical displacement of the shaft 28. Thus a limit is provided to the resiliency of the upper webbing 27 preventing possible breakage or distortion thereof.

It will be noted however that a similar stop member may be provided also for the shaft 29 suitably secured to the back frame member 13 in order to further protect the upper webbing strips against extreme distortion.

In operation the initial load when the chair is used is taken up by the resilient webbing strips 27, which due to the floating shaft support gives a spring action or yielding support for the chair seat which is commensurate with the coiled springs hereto employed in this construction.

Naturally a degree of resiliency is also obtained from the resilient padding members 35 and 36 employed above the webbing strips 27, and also between said webbing strips and the lower chair webbing 19. Further, after the initial compression of webbing 27, engagement is had between webbing 27 and the lower chair webbing 19 whereby added support is given to the first mentioned webbing 27.

While webbing 19 is itself resilient to a limited extent, yet the greater degree of resiliency resides in the upper webbing 27 supported by the floating shafts 28 and 29. It is this upper webbing floating construction that actually provides a substitute resiliency for the coiled springs heretofore employed in chair construction, but at present not available therefor.

Having described my invention, reference should now be had to the claims which follow for determining the scope thereof.

I claim:

1. A chair construction comprising a hollow substantially rectangular frame with depending legs, a lower webbing seat supporting member secured to said frame, a plurality of strips of material longitudinally disposed and yieldingly secured within said frame in spaced relation to said lower webbing, looped portions on opposite ends of said strips, forming a part thereof yielding cylindrical shafts disposed within said frame and through said loops, and looped means secured to and extending from said frame through which the ends of said shafts are disposed and supported, said upper strips being adapted to yieldingly sustain a load, while said lower member is adapted for supporting cooperation therewith after initial downward movement thereof.

2. A chair construction comprising a hollow substantially rectangular frame with depending legs, a lower webbing seat supporting member secured to said frame, a plurality of strips of material longitudinally disposed and yieldingly secured within said frame in spaced relation to said lower webbing, looped portions on opposite ends of said strips, forming a part thereof yielding cylindrical shafts disposed within said frame and through said loops, looped means secured to and extending from said frame through which the ends of said shafts are disposed and supported, and looped movement limiting means secured to and depending from said frame for loosely engaging said dowel sticks to prevent undue distortion and movement of said upper supporting strips, said upper strips being adapted to yieldingly sustain a load, while said lower member is

adapted for supporting cooperation therewith after initial downward movement thereof.

3. A chair construction comprising a hollow substantially rectangular frame with depending legs, a lower webbing seat supporting member secured to said frame, a plurality of strips of material longitudinally disposed and yieldingly secured within said frame in spaced relation to said lower webbing, looped portions on opposite ends of said strips, forming a part thereof yielding cylindrical shafts disposed within said frame and through said loops, looped means secured to and extending from said frame through which the ends of said shafts are disposed and supported, and resilient padding material provided upon said strips and between the same and said lower webbing, said upper strips being adapted to yieldingly sustain a load, while said lower member is adapted for supporting cooperation therewith after initial downward movement thereof.

4. A chair construction comprising a hollow frame with depending legs, front and rear cross bars secured to said frame, a lower webbing seat supporting member consisting of a plurality of transverse strips of material secured at their ends to said frame, and a plurality of longitudinal strips of material interwoven therewith, with their ends loosely drawn over and around said cross bars and secured to said frame, a plurality of strips of material longitudinally disposed and yieldingly secured within said frame in spaced relation to said lower webbing, looped portions on opposite ends of said strips, yielding cylindrical shafts disposed within said frame and through said loops, and looped means secured to and extending from said frame through which the ends of said shafts are disposed and supported, said upper strips being adapted to yieldingly sustain a load, while said lower member is adapted for supporting cooperation therewith after initial downward movement thereof.

5. A chair construction comprising a hollow frame with depending legs, notched front and rear cross bars secured to said frame, a lower webbing seat supporting member consisting of a plurality of transverse strips of material secured at their ends to said frame, and a plurality of longitudinal strips of material interwoven therewith, slidably disposed through said cross bar notches and with their ends secured to said frame, a plurality of strips of material longitudinally disposed and yieldingly secured within said frame in spaced relation to said lower webbing, looped portions on opposite ends of said strips, yielding cylindrical shafts disposed within said frame and through said loops, and looped means secured to and extending from said frame through which the ends of said shafts are disposed and supported, said upper strips being adapted to yieldingly sustain a load, while said lower member is adapted for supporting cooperation therewith after initial downward movement thereof.

6. A chair construction comprising a hollow frame with depending legs, notched front and rear cross bars secured to said frame, a lower webbing seat supporting member consisting of a plurality of transverse strips of material secured at their ends to said frame, and a plurality of longitudinal strips of material interwoven therewith, slidably disposed through said cross bar notches and with their ends secured to said frame, yielding shafts disposed within said frame intermediate said cross bars and the ends of said latter strips, over which the same are yieldingly

and resiliently supported, and a plurality of strips of material longitudinally disposed and yieldingly secured within said frame in spaced relation to said lower webbing, looped portions on opposite ends of said strips, yielding secondary shafts disposed within said frame and through said loops, and looped means secured to and extending from said frame through which the ends of said secondary shafts are disposed and supported, said upper strips being adapted to yieldingly sustain a load, while said lower member is adapted for supporting cooperation therewith after initial downward movement thereof.

7. A furniture construction comprising a substantially rectangular frame with depending legs, a lower webbing member secured at its edges to said frame, an upper webbing member looped at its ends loosely provided within said frame in yielding spaced relation to said lower webbing, floating supporting shafts disposed within said frame and extending through the loops, and means on said frame yieldingly supporting said shafts, said upper member being adapted to yieldingly sustain a load, while said lower member is adapted for supporting cooperation therewith after initial downward movement thereof.

8. A chair construction comprising a hollow rectangular frame with depending legs, a lower webbing supporting member secured at its edges to said frame, an upper supporting member looped at its ends loosely provided within said frame in yielding spaced relation to said lower webbing, longitudinally and vertically yielding supporting shafts disposed within said frame and through

the loops, and means secured to said frame for yieldingly retaining said shafts, said upper member being adapted to yieldingly sustain a load, while said lower member is adapted for supporting cooperation therewith after initial downward movement thereof.

9. A chair construction comprising a hollow rectangular frame with depending legs, a lower webbing supporting member secured at its edges to said frame, an upper supporting member looped at its ends loosely provided within said frame in yielding spaced relation to said lower webbing, longitudinally and vertically yielding supporting shafts disposed within said frame and through the loops, means secured to said frame for yieldingly retaining said shafts, and movement limiting means secured to said frame and loosely engaging said shafts to prevent undue distortion and movement of said upper supporting member, said upper member being adapted to yieldingly sustain a load, while said lower member is adapted for supporting cooperation therewith after initial downward movement thereof.

10. A furniture construction comprising a hollow frame with depending legs, a lower webbing member secured at its edges to said frame, an upper webbing member looped at its ends loosely provided within said frame in yielding spaced relation to said lower webbing, floating supporting shafts disposed within said frame and extending through the loops, and means on said frame yieldingly supporting said shafts.

HAROLD ROBINSON.
